UNITED STATES PATENT OFFICE.

TREVOR M. CAVEN, OF MILWAUKEE, WISCONSIN, ASSIGNOR TO A. J. LINDEMANN & HOVERSON CO., OF MILWAUKEE, WISCONSIN.

ELECTRIC HEATING ELEMENT.

1,074,928.

Specification of Letters Patent.

Patented Oct. 7, 1913.

Application filed August 1, 1911. Serial No. 641,824.

To all whom it may concern:

Be it known that I, TREVOR M. CAVEN, a citizen of the United States, and resident of Milwaukee, in the county of Milwaukee and State of Wisconsin, have invented certain new and useful Improvements in Electric Heating Elements; and I do hereby declare that the following is a full, clear, and exact description thereof.

10 My invention relates to that type of electric heating elements in each of which there is radiation from energized resistance through insulation of the same contained in a plate of refractory material to which 15 a metallic surface plate may or may not be connected in intimate contact with the same and said insulation, said invention consisting in what is herein particularly set forth with reference to the accompanying drawings and pointed out in the claim of this 20 specification, its object being to economically increase efficiency of such an element by means of a peculiar resistance and insulation for the same.

25 Figure 1 of the drawings is a diagram illustrating a preferred disposition of a pair of resistance devices in a refractory plate of an electric-heating element, and a switch by which to employ said devices in multiple 30 or series so as to vary the degree of heat emanating from said element; Fig. 2, a plan view partly in horizontal section illustrating fragments of the refractory plate, one of the resistance devices and insulation for 35 the same in said plate; Fig. 3, a transverse sectional view, indicated by line 3—3 in Fig. 2, and including a showing of a fragment of a metallic surface plate in intimate contact with the refractory plate and insulation 40 aforesaid; Fig. 4, a plan view of a fragment of the aforesaid resistance device on an enlarged scale; Fig. 5, a diagram illustrating a disposition of another form of resistance device in a refractory plate and the electric connections therewith; Fig. 6, a view similar to Fig. 2, illustrating the 45 plaiting of a resistance ribbon in the second form of resistance device, and Figs. 7 and 8, sectional views respectively indicated by 50 lines 7—7 and 8—8 in Fig. 6, a fragment of a metallic surface plate being included in Fig. 8.

Referring by numerals to the drawings, 9 indicates a refractory plate of molded asbestos or other suitable material provided

with recesses inward from one side thereof containing insulation 10 in which one or more resistance devices are embedded. This combination constitutes an electric heating element provided with a metallic 60 surface plate 11 permanently secured thereto in intimate contact with said refractory plate and insulation. In Fig. 1 a pair of resistance devices 12, 13 are shown as having one terminal of each in connection with a contact 14 of a pole-changer switch 15 that is coupled to binding-posts 16, 17 of positive and negative current wires. The other terminal of the resistance device 12 is in permanent connection with a binding- 65 post 18, to which a branch of the negative current wire is also connected, and the other terminal of the resistance device 13 is in connection with a contact 14' of said switch. 70

The arms of the pole-changer switch being set on the contacts 14, 14', the resistance devices 12, 13, are connected in multiple, the positive current dividing at said contact 14 to flow through both of said resistance devices to the negative current wire then temporarily connected, through said switch, with the resistance device 13. When the resistance devices are thus connected in multiple, the greatest degree of heat emanates from the herein described electric 85 heating element, but if the switch be adjusted to connect the binding-post 16 with the contact 14' and break the connection between the binding post 17 and said contact, 90 said resistance devices will be connected in series to obtain the least degree of heat from said element. To obtain a medium degree of heat, the switch is adjusted to remain on contact 14 but be off contact 14' so that only the resistance device 12 is in circuit. Other 95 means may be employed in connection with the aforesaid resistance devices for throwing one or both of the same into circuit, the general construction and disposition of parts as thus far described being common 100 in the art to which my improvements pertain.

Each of the aforesaid resistance elements is flat and zigzag in the insulation 10, this insulation being a solidified plastic cement 105 compound of high thermal conductivity designed to unite the refractory and metallic plates aforesaid. The insulation in its plastic state is subjected to a high pressure in the refractory plate, and between this 110

plate and the metallic plate, all the components of the improved electrical heating element being combined in a single solid mass, this being an important feature of my invention.

As shown in Figs. 2, 3 and 4, each resistance device may be a flat stiff zigzag strip, and as shown in Fig. 4, this strip being preferably slit at intervals thereof transversely from its edges for a portion of its width, the slits from one edge alternating with those from the opposite edge, whereby tortuosity of current travel is increased in order to provide for the utilization of a high percentage of the heat energy of said current.

The resistance device shown in Figs. 6, 7 and 8, is a zigzag strip 13' of resistance ribbon laid flat in the aforesaid insulation, the stretches of the ribbon being alternately upon different parallel planes, thereby forming a coreless flat helix, as best shown in Fig. 8, and the laying of said ribbon is such as to utilize the greatest amount of its surface for the distribution of heat energy.

In any form of resistance device or devices, the arrangement of the same with the insulation thereof is such as to provide for the greatest possible radiation from the heating element, the metal surface plate, being in

close proximity to the resistance device or devices of said element, in order to obtain the best results, and by the employment of the flat zigzag resistance above specified, a high efficiency is obtained because of the greater than ordinary surface exposed to the insulation, owing to the fact that the current density per each square inch of cross-sectional area is the same at all points of the flat resistance strip or ribbon aforesaid.

I claim:

An electric heating element comprising a plate of refractory material provided with recesses in its face, a solidified plastic insulating filler of high thermal conductivity for the plate recesses, the same forming a homogeneous mass with relation to said plate, a coiled resistance element embedded within the plastic insulation, and a metallic surface plate in cohesive relation with the plate and insulation.

In testimony that I claim the foregoing I have hereunto set my hand at Milwaukee in the county of Milwaukee and State of Wisconsin in the presence of two witnesses.

TREVOR M. CAVEN.

Witnesses:

JOHN S. BRENNAN,
WM. L. PIEPLOW.
